(57) **CLAIM**

The ornamental design for an HVAC control device display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of an HVAC control device display screen or portion thereof with graphical user interface showing our new design according to a first embodiment.

FIG. 2 is a front view of an HVAC control device display screen or portion thereof with graphical user interface showing our new design according to a second embodiment.

FIG. 3 is a front view of an HVAC control device display screen or portion thereof with graphical user interface showing our new design according to a third embodiment; and,

FIG. 4 is a front view of an HVAC control device display screen or portion thereof with graphical user interface showing our new design according to a fourth embodiment.

The outer perimeter broken lines illustrate portions of an HVAC control device or HVAC control device display screen or portion thereof that form no part of the claimed design. The remaining evenly-spaced broken lines illustrate portions of the graphical user interface that form no part of the claimed design.
